UNITED STATES PATENT OFFICE.

CHARLES E. DE LANCEY AND JEROME L. RITTER, OF NEWPORT, PENN-SYLVANIA.

COMPARTMENT VESSEL.

SPECIFICATION forming part of Letters Patent No. 664,181, dated December 18, 1900.

Application filed July 7, 1900, Serial No. 22,887. (No model.)

To all whom it may concern:

Be it known that we, CHARLES E. DE LANCEY and JEROME L. RITTER, citizens of the United States, residing at Newport, in the county of Perry and State of Pennsylvania, have invented certain new and useful Improvements in Compartment Vessels; and we do declare the following to be a full, clear, and exact description of the invention, such as will enable others skilled in the art to which it appertains to make and use the same.

Our invention relates to improvements in kegs and other vessels or receptacles for gaseous liquids—such as beer, ale, porter, and the like.

One object of the invention is to provide a vessel having a series of compartments meeting at a common center combined with means whereby the contents of either compartment may be drawn off at will independently of the contents of the other compartments.

A further object of the invention is to provide means whereby the several compartments may be charged with air or gas from the exterior through the same controlling devices used for drawing off the contents and whereby the liquid contents of either vessel may be drawn off with or without air or gas at will.

30 A still further object of the invention is to provide means for cutting off both the flow of the liquid and air or gas when the draft-tube is removed and to let on the flow of the same when the draft-tube is inserted for use, the operation of inserting and removing the tube effecting the automatic actuation of the cut-off.

40 A still further object of the invention is to provide a compartment barrel, keg, or vessel of this character which is comparatively simple of construction and may be conveniently shipped full or empty.

45 With these and other minor objects in view the invention consists in certain novel features of construction, combination, and arrangement of parts, as will be hereinafter more fully described, and particularly pointed out in the appended claims.

In the accompanying drawings, Figure 1 is

a front view of an ordinary beer-keg embodying our invention. Fig. 2 is a longitudinal section of the same. Fig. 3 is a cross-section thereof. Fig. 4 is a detail longitudinal section through a portion of the draft-tube, showing the plunger or cut-off arranged to shut off the flow of liquid and air or gas. Fig. 5 is a cross-section through the draft-tube on the line of the liquid-openings. Fig. 6 is a similar view on the line of the air-tubes and openings. Fig. 7 is a detail view showing the bayonet-joint connection between the faucet and draft-tube. Figs. 8 and 9 are detail sectional views showing the arrangement of the ports for respectively drawing off the liquid contents of the compartment with and without air or gas. Fig. 10 is a perspective view of the faucet-valve or turning plug.

Like reference characters indicate corresponding parts throughout the several views.

For convenience of illustration and description we have shown our invention applied to an ordinary beer-keg; but it will of course be understood that it can be applied to a vessel or container of any description suitable for holding liquids of the character specified.

The numeral 1 in the drawings represents the staves, and 2 the heads, of an ordinary beer-keg embodying our invention. The interior of this keg is divided into a number of compartments 3 by radial partitions 4, secured to the staves and heads and meeting at a common center, being secured at their inner ends to a longitudinal draft-tube 5, arranged, preferably, in the axis of the keg and stepped in the head. The partitions 4 may be stepped in flutes or grooves in the staves, heads, and central draft-tube and fixed in any way, and in the case of a beer-keg the joints may be closed by pitching the interior of the same in the usual manner. In the present instance we have shown the partitions suitably secured at their outer ends to the staves and provided in their inner ends with grooves 6 to receive longitudinal tongues or flanges 7, radiating from the periphery of the central draft-tube. The said central draft-tube is secured against longitudinal movement in one direction by a screw-cap 8 engaging the rear

projecting end thereof, and a similar screw-cap 9 is adapted to be employed to engage the front projecting end thereof when the faucet is removed to seal the draft-tube and prevent escape of the contents of the keg.

The draft-tube 5 is provided at its front end between the adjacent partitions with two annular series of ports, a series of liquid-exhaust ports 10 and a series of air or gas inlet and exhaust ports 11, the latter arranged in advance of the former. The ports 11 are in communication with a series of radial tubes 12, fixed to the draft-tube and extending outwardly to points in close proximity to the staves or wall of the keg or vessel. These tubes serve as means whereby air or gas may be supplied to the compartments and also drawn therefrom, as hereinafter described.

The faucet 13 is adapted to be inserted and withdrawn through the front end of the draft-tube and is provided with two independent longitudinal passages 14 and 15, both of which communicate with the socket or chamber of the turning plug or valve 16, which controls the discharge of the contents of the keg therefrom. The passage 14 is provided at its inner end with a port 14', which is adapted to be brought into register with either of the openings 10 and terminates at its outer end in the valve-socket. The passage 15 is likewise provided at its inner end with a port 15', which is adapted to be brought into register with either one of the air or gas ports 11, but extends at its outer end beyond the plug-valve socket and is provided with a port 15², opening directly to the atmosphere. The ports 10 and 11 and 14' 15' are respectively located in corresponding planes, so that when one of the ports 14' is brought into register with a port 10 one of the ports 15' will also be brought into register with a port 11, thus allowing both liquid and air or gas to discharge from a compartment at one and the same time when the valve or turning plug is properly arranged to permit of such discharge. The faucet is adapted to be turned to bring the ports into position to coincide with the ports 14' 15' of either compartment, so that the contents of one compartment may be drawn off without interfering with the contents of the other compartments, or liquid of one kind may first be drawn from one compartment and then mixed with a different liquid from another, as desired. It will of course be understood that the compartments may contain the same kind of liquid, several varieties of a liquid of one kind, or entirely different liquids and the same dispensed separately from one keg or vessel.

To facilitate the setting of the faucet when turned and to lock the same in proper position, a bayonet-joint connection between the draft-tube and faucet may be provided. This consists of an annular groove 17, formed upon the interior of the outer end of the draft-tube and communicating with a series of

outwardly-projecting notches 18, equal in number to and located in line with each of the series of ports 14' 15'. Between two of these notches is an outlet-groove 19, through which a pin 20 on the faucet is adapted to pass when inserting it into and withdrawing it from the groove 17. When the pin is arranged in this groove 17, it may be set into either one of the notches 18 by turning the faucet to the desired extent and drawing it endwise in an outward direction, when the pin will enter the notch and hold the faucet against rotation. A reverse movement withdraws the pin from the notch to allow it to be set in either one of the other notches or withdrawn through the groove 19. The setting of the faucet may also be facilitated by marking on the head of the keg the centers of the compartments, as indicated by the arrows in Fig. 1.

The turning plug or valve 16 is provided with a passage 21, opening through its lower end and formed at its upper end with a lateral port 21', opening through the side of the valve. This port is adapted to be brought into coincidence with the passage 14 in the faucet to bring one of the ports 10 into register with said passage 14 and the passage 21 to form an uninterrupted duct or channel for the outflow of the liquid contents of either one of the compartments. The valve is also provided with a port 22, extending diametrically therethrough and at right angles to the passage 21. This port 22 is adapted to be brought into register with the passage 15 to provide an uninterrupted duct or channel for the inlet or outflow of air through one of the tubes 12, its port 11, and the passage 15 and ports 15' 15². The port 21' extends obliquely or diagonally with respect to the port 22, so that the valve 16 is adapted to have four positions—one in which both ports 21' and 22 may be brought into working position to register with the passages 14 and 15, and thereby provide for the discharge of both liquid and air, as shown in Figs. 2 and 8, one in which the port 22 is turned at an angle to the passage 15 to cut off the outflow of air, while the port 21' is still in register with passage 14 to allow the liquid to discharge, as shown in Fig. 9, one in which the port 21' faces reversely to the passage 14 to bring the opposite end of the port 22 inwardly or away from port 15², but to bring said port 22 in line with the passage 15 and port 15² and the port out of line with passages 14, so as to allow air to be forced into either compartment, and the last a blank position in which both ports 21' 22 are out of register with the passages 14 15 to cut off both the flow of liquid and air. When it is desired to allow the liquid to discharge with air, the valve is turned so as to bring the port 22 in line with the passage 15 and present nearly the full area of the port 21' to the passage 14. When, on the other hand, it is desired to allow only liquid to discharge, the

valve is given a quarter-turn to bring the port 22 at right angles to the passage 15 and present approximately three-quarters of the full area of the port 21' to the passage 14, as shown in Fig. 9. To place the valve in position to permit of air or gas being supplied to or discharged alone from either compartment, said valve is given a half-turn from the position shown in Fig. 8, which will bring the port 21' to a reverse position, in which it faces outwardly or away from the passage 14, and the port 22 will also be reversed, but will still be in register with the passage 15. By this means the passage 14 will be closed and the passage 15 opened, and if it be desired to charge the compartment with which said passage 15 is in communication with air or gas this operation may be readily accomplished by inserting a fitting leading from a pump or storage-reservoir into the port 15² and allowing the air or gas under pressure to enter thereinto. The flow of both air or gas and liquid may be cut off by turning the valve to a position in which the wall of the valve opposite the port 21' faces the passage 14 and the port 22 takes a diagonal position to the port 15 and does not connect it with the port 15². The form of valve shown is deemed preferable, but other types of valve designed to subserve a similar function may be used.

As heretofore stated, the faucet 13 is applied and removed by sliding it in and out of the front end of the draft-tube 5, which is closed by the cap 9 when the faucet is withdrawn. To automatically cut off the outflow of the liquid and air or gas from all the compartments when the faucet is removed, we provide a plunger-valve 23, mounted to slide in the cylinder in rear of the faucet and normally pressed forward by a spiral spring 24, attached to said valve and to the cap 8, so as to be readily withdrawn whenever desired by detaching said cap and pulling it outwardly. The faucet 13 when placed in the draft-tube forces the plunger rearwardly or retracts it, but when said faucet is removed the plunger-valve is forced forward by the spring and automatically closes both sets of ports 10 and 11. By this means all waste is prevented and the keg or vessel may be shipped when full with facility and tapped by simply inserting a faucet of the construction described into the draft-tube.

The valves and coöperating parts may be provided with packing to prevent leakage, and the central draft-tube may be constructed of metal or rubber. When rubber is employed, it is preferable to provide a center screw and washer at each end, so that by simply tightening the screw the diametrical area of the tube may be increased to fit tightly and take up wear.

The keg or vessel may be filled from one bung or have each compartment provided with a bung, and of course each compartment should also be provided with a vent.

The vessel may be set on the side or on end, as described and according to the use to which it is to be put, and each compartment can be drained to the last drop.

70

From the foregoing description, taken in connection with the accompanying drawings, the construction and mode of operation of the invention will be readily understood without a more extended explanation, and it will be seen that a compartment vessel which is comparatively simple of construction, efficient in operation, and capable of being handled or transported either full or empty is provided.

75

While the preferred embodiment of the invention is herein disclosed, it will of course be understood that the construction may be modified within the scope of the invention without departing from the spirit or sacrificing any of the advantages thereof.

80

Having thus fully described our invention, what is claimed, and desired to be secured by Letters Patent of the United States, is—

85

1. A compartment vessel having a draft-tube provided near its front end with ports communicating with the several compartments, a faucet adapted to be inserted and removed through the front end of the tube, a cap closing the rear end of the tube, a valve for closing the ports upon the removal of the faucet, and a spring connected with the cap and valve, substantially as set forth.

90

2. A compartment vessel having a central draft-tube provided with independent sets of ports for liquid and air or gas, said ports communicating with the several compartments, radial tubes in the compartments and communicating with the air-ports, and a faucet provided with independent passages for said ports and a valve controlling both passages, whereby air or gas and liquid may be drawn independently or together through said tube, substantially as set forth.

95

3. A compartment vessel having a central draft-tube provided with ports communicating with the several compartments and having an open end formed on its interior with an annular groove, a series of communicating notches and a guide-groove leading to said annular groove, and a faucet insertible and withdrawable through said open end of the tube and controlling said ports and carrying a pin coöperating with said grooves and notches, substantially as set forth.

100

4. A compartment vessel having a central draft-tube extending axially therethrough and having ports communicating with the several compartments, caps to close the ends of the tube, and a faucet insertible and withdrawable through one end of the tube and controlling said ports, substantially as set forth.

105

5. A compartment vessel having a central draft-tube extending axially therethrough and having ports communicating with the several compartments, caps to close the ends of the tube, a faucet insertible and withdraw-

110

115

120

125

130

able through one end of the tube and controlling said ports, and a valve for automatically closing said ports upon the reversal of the faucet, said valve being insertible and 5 withdrawable through the other end of the tube, substantially as set forth.

In testimony whereof we have hereunto set

our hands in presence of two subscribing witnesses.
